(57) **CLAIM**

The ornamental design for a downspout retention clip, as shown and described.

DESCRIPTION

FIG. 1 is a top view of a downspout retention clip; FIG. 2 is bottom view of the downspout retention clip of FIG. 1;

FIG. 3 is a front elevation view of the downspout retention clip of FIG. 1;

FIG. 4 is a rear elevation view of the downspout retention clip of FIG. 1;

FIG. 5 is a right side elevation view of the downspout retention clip of FIG. 1;

FIG. 6 is a left side elevation view of the downspout retention clip of FIG. 1;

FIG. 7 is a perspective view of the downspout retention clip of FIG. 1;

FIG. 8 is an environmental view of the downspout retention clip of FIG. 1 coupled to a downspout of a gutter system; FIG. 9 is another environmental view of the downspout retention clip of FIG. 1 coupled to a downspout of a gutter system; and,

FIG. 10 is another environmental view of the downspout retention clip of FIG. 1 coupled to a downspout of a gutter system.

Broken lines in the drawings illustrate portions of the downspout retention clip and environmental artifacts that form no part of the claimed design.

1 Claim, 5 Drawing Sheets
